UNITED STATES PATENT OFFICE

111,804

DESIGN FOR A LINK FOR A FLOOR MAT

Harry W. Bell, Akron, Ohio, assignor to Durable Mat Company, Seattle, Wash., a corporation of Washington

Application December 17, 1937, Serial No. 73,681

Term of patent 7 years

To all whom it may concern:

Be it known that I, Harry W. Bell, a citizen of the United States, residing at Akron, in the county of Summit and State of Ohio, have invented a new, original, and ornamental Design for a Link for a Floor Mat, of which the following is a specification, reference being had to the accompanying drawing, forming a part thereof.

In the drawing:

The figure is a perspective view of a link for a floor mat showing my new design.

The characteristic features of my design reside in the link, as shown, having end portions of generally cylindrical form connected by an intermediate portion provided with four transverse ribs

and intervening transverse grooves at the upper surface thereof, said ribs and grooves being of substantially equal width, the outer two of said ribs blending at their lower edges with said cylindrical end portions, and one centrally located relatively large transverse rib at the bottom portion thereof, said bottom rib, together with the under portions of said end portions, forming three relatively large curved surfaced transverse ribs on the bottom of the link.

I claim:

The ornamental design for a link for a floor mat, substantially as shown and described.

HARRY W. BELL.
